CLAIM

The ornamental design for a biological sample collection card as shown and described.

DESCRIPTION

FIG. 1 is a perspective view principally of the front side of a biological sample collection card showing our new design; FIG. 2 is an orthogonal view of the left side of the design of FIG. 1;

FIG. 3 is an orthogonal view of the right side of the design of FIG. 1;

FIG. 4 is an orthogonal view of the front of the design of FIG. 1;

FIG. 5 is an orthogonal view of the rear of the design of FIG. 1;

FIG. 6 is a top plan view of the design of FIG. 1; and, FIG. 7 is a bottom plan view of the design of FIG. 1.

1 Claim, 6 Drawing Sheets
